PENDANT TYPE BAROMETER OR THE LIKE

Howard S. Taylor, Fox River Grove, Ill., assignor to Air-guide Instrument Company, Chicago, Ill., a corporation of Illinois

Application July 5, 1955, Serial No. 36,804

Term of patent 7 years

(Cl. D52—7)

The figure is a front perspective view of a pendant type barometer or the like showing my new design.

I claim:

The ornamental design for a pendant type barometer or the like, as shown.
